United States Patent Office

Des. 224,080
Patented July 4, 1972

224,080

PULLING TOOL OR SIMILAR ARTICLE

Bruce F. Lawson, 2028 Angling Road,
Corfu, N.Y. 14036

Filed Dec. 4, 1970, Ser. No. 26,281

Term of patent 14 years

Int. Cl. D8—05

U.S. Cl. D8—14

Fig. 1.

Fig. 2.

Fig. 3.

Fig. 4.

FIG. 1 is a front elevational view of a pulling tool or similar article, showing my new design, the opposite rear side being identical to that shown;

FIG. 2 is a side elevational view thereof, the opposite side being identical to the side shown;

FIG. 3 is a top plan view thereof; and

FIG. 4 is a bottom plan view thereof.

I claim:

The ornamental design for a pulling tool or similar article, substantially as shown and described.
